UNITED STATES PATENT OFFICE.

HENRY E. BILLMAN AND FRANK A. KELL, OF ST. LOUIS, MISSOURI, ASSIGNEES TO
INDUSTRIAL TRACK CONSTRUCTION COMPANY, OF ST. LOUIS, MISSOURI, A COR-
PORATION OF MISSOURI.

CAR-BUMPER.

1,356,959.

Specification of Letters Patent. Patented Oct. 26, 1920.

Application filed February 18, 1919. Serial No. 277,739.

To all whom it may concern:

Be it known that we, HENRY E. BILLMAN and FRANK A. KELL, citizens of the United States, residing at the city of St. Louis, 5 State of Missouri, have jointly invented a certain new and useful Improvement in Car-Bumpers, of which the following is a specification, reference being had to the accompanying drawing, forming a part 10 thereof.

This invention relates generally to railway-track equipment, and, more particularly, to a certain new and useful improvement in car-bumpers, the chief object of 15 our present invention being to provide a car-bumper which is simple in form and construction and capable of manufacture and production at a low cost, which may be conveniently, quickly, and inexpensively oper- 20 atively installed upon the track, which is strong, rugged, and durable to efficiently withstand ordinary or average shocks or impacts, and which, when installed upon the track, forms an effective obstruction imped- 25 ing further progress or travel of the car or cars.

With the above and other objects in view, our invention resides in the novel features of form, construction, arrangement, and 30 combination of parts hereinafter described and afterward pointed out in the claims.

In the accompanying drawing,

Figure 1 is a perspective view of a section of a railway-track equipped with a pair 35 of car-bumpers constructed in accordance with and embodying our invention;

Fig. 2 is a side elevational view of one of the sections of the bumper; and

Fig. 3 is a sectional view through the bumper as in operatively installed position on the track, taken approximately on the line 3-3, Fig. 2.

Referring more particularly to the said drawing, in which like reference characters refer to like parts throughout the several views, our new bumper comprises a pair of co-operating matching sections A—A, similar in form and construction. Each section A is substantially of plate forma- 45 tion and, in finished form, has the shape and contour illustrated, being of greatest altitude at its longitudinal center and of greatest lateral width at its base.

Each section A may be pressed, cast, or

otherwise formed to finished shape, and in 55 its production a portion 1 at the base of the plate is suitably formed to project outwardly of the general plane of the outer face of the plate to provide upon the inner side of the plate an open-ended groove or channel 60 2 extending throughout the lateral width of the plate at its base and of a depth and contour conforming, as best seen in Fig. 3, to approximately one-half of the contour of the ball of the substantially standard rail 65 B, the plate being extended, as at 3, beneath the groove 2 to fit and engage smoothly throughout its base with the web of the rail, as shown.

From a point on each of its side edges 70 slightly above the rail-fitting groove 2, as best seen in Figs. 1 and 2, the body of the plate of each section A is cut away inwardly and upwardly on a radius conforming approximately to the radius of the standard car-wheel and thereby correspondingly arc-shaped at opposite side edges. Presented outwardly from the body of the plate on its outer face, and extending around the plate, except, as shown, along the lower 80 edge of its rail-web engaging-portion 3, is a substantially continuous reinforcing or strengthening marginal or edge flange 4, the portions of said flange which extend along the opposite arc-shaped edges of the plate 85 being correspondingly curved and forming therewith the opposite impact-receiving end walls 5 of the bumper-section A, each of which said end walls has, as described, an arc-shaped face substantially conforming in 90 curvature to the circumferential curvature of the standard car-wheel.

Adjacent the upper edge of the plate and approximately centrally intermediate the said opposite end walls 5—5, the plate of the 95 section is provided upon its outer face with a boss or enlargement 6 preferably laterally elongated to merge at opposite ends into the marginal flange 4, as seen in Figs. 1 and 2, the plate and its said boss 6 being suitably 100 transversely apertured, as at 7, to receive and accommodate a securing-bolt 8.

Also formed on the outer face of the plate and merging at their ends, as shown, into said groove-forming base-portion 1 and into 105 the edge flange 4 and boss 6, are longitudinally disposed reinforcing or strengthening ribs 9, the plate being further provided upon

the outer face of its said rail-web engaging extension 3 with a plurality of relatively short longitudinally extending strengthening ribs 10. And at suitable intervals along 5 said extension 3 and intermediate the ribs 10, the plate is formed on its outer face with bosses or the like 11, the body of the plate and each of its said bosses 11 being transversely apertured, as at 12—12, to accommodate 10 date suitable clamping or fastening bolts 13.

The inner face of each section A, above its said groove 2, is substantially smooth and flat, and in use or practice a pair of the sections A is adapted for conjoint installation 15 upon the rail to form or provide the complete bumper. In such installation, two of the sections A, in reverse arrangement relatively to each other, are disposed in upright position upon the rail with the major portions 20 of their inner faces registering and abutting flatwise together, their said grooved portions 1 closely hugging and embracing the ball of the rail, and their lower extensions 3 fitting upon opposite sides of the web 25 of the rail. The two sections A, so disposed, are then rigidly clamped or fastened together and to the rail by means of the clamping or fastening-bolts 13, which are passed through the bolt-holes or apertures 12 and 30 registering holes provided in the web of the rail for the purpose, the two sections A being additionally fastened together in such clamping engagement with the rail by means 35 of a bolt or the like 8 passed through the then registering bolt-holes or apertures 7.

The bumpers are adapted to be employed or installed in pairs transversely aligned across the track, and when installed as described, it has been found that our new bumpers provide a most efficient obstruction 40 impeding further progress or travel of the car or cars, the said opposite arc-shaped end faces of the bumpers extending or lying in the vertical planes of the rails and the bumpers being of a height to receive the impact 45 or shock from the lower rear quadrants of the wheels and prevent or hold the car from rolling over the bumpers. If desired in any particular installation, the bumper-sections 50 may be clamped together and to the rail by special bolts designed to break or give way when the bumpers are subjected to any extraordinary shock or impact, the bumpers being thereby permitted to gradually move 55 back on the rails and the danger of misplacing the car-trucks under such extraordinary shock or impact being thus obviated.

The bumper-sections A, being similar in form and construction, may be made from 60 one pattern, there being no rights or lefts and the sections being interchangeable and reversible to meet the requirements of any installation. Our new bumpers may be manufactured and produced at low cost and, 65 as will be evident, may be readily and con-

veniently installed at little expense. We may add that not only is the cost of maintenance of our bumpers practically nominal, but by the use and employment of our bumpers, the expense and annoyance of frequent 70 replacements of bent rails, wooden blocks, and other more or less expensive parts, now generally necessitated, so far as we are aware, with other bumpers, is substantially entirely done away with. 75

It is to be understood that changes in the form, construction, arrangement, and combination of the several parts of our bumper may be made and substituted for those herein shown and described without departing 80 from the nature and principle of our invention.

Having thus described our invention, what we claim and desire to secure by Letters Patent is:

1. A car-bumper comprising a pair of sections adapted to seat upon and extend vertically in the plane of the rail, the sections having registering end walls arcuated to conform approximately to the curvature of a 90 car-wheel.

2. A car-bumper comprising a pair of sections adapted to seat upon and extend vertically in the plane of the rail, the sections being of like formation and having at each 95 end registering end walls arcuated to conform approximately to the curvature of a car-wheel.

3. A car-bumper comprising a pair of sections adapted to seat upon and extend vertically in the plane of the rail, the sections having registering end walls arcuated to conform approximately to the curvature of a car-wheel, and means for engaging the sections and the rail for rigidly clamping the 100 sections together and to the rail.

4. A car-bumper including a pair of sections adapted to seat upon the rail, each section being integrally extended for engagement with both a part of the ball and one 110 side of the web of the rail.

5. A car-bumper including, in combination with a rail, a pair of sections adapted to seat upon the rail, each section being integrally extended for engagement with both a part of the ball and one side of the web of the rail, and means projecting through the extended portions of the sections and the web of the rail for clamping the sections and rail together. 115

6. A car-bumper including, in combination with a rail, a pair of coöoperating companion sections of plate formation adapted to seat in upright registering position upon the rail, each section having an integral extension adapted for engagement with both a part of the ball and one side of the web of the rail, and means projecting through the extensions and the web of the rail for clamping the sections and rail together. 120

7. A car-bumper comprising, in combination with a rail a pair of separable sections substantially of plate formation adapted to seat in upright flatwise abutting position upon and embrace the ball and web of the rail, each section being grooved at its base in conformation with approximately one-half of the ball of the rail and having a base-extension adapted for engagement with the web of the rail, and means extending through said extensions and the web of the rail for separably clamping the sections together and to the rail.

8. A car-bumper comprising, in combination with a rail a pair of sections substantially of plate formation adapted to seat in upright flatwise abutting position upon and embrace the ball and web of the rail, each section being grooved at its base in conformation with approximately one-half of the ball of the rail and having a base-extension adapted for engagement with the web of the rail, means extending through said extensions and the web of the rail for clamping the sections together and to the rail, and additional means extending through the sections above the rail for fastening the sections together in clamping engagement with the rail.

9. A car-bumper section of plate formation adapted to seat in upright position upon the rail, the section being grooved at its base in conformation with approximately one-half of the ball of the rail and having a base-extension adapted for engagement with one side of the web of the rail.

10. A car-bumper section provided upon its outer face with strengthening ribs, the section being adapted to seat upon and

closely hug a part of the ball and one side 40 of the web of the rail.

11. A car-bumper section of plate formation provided upon one face with strengthening ribs, the section being adapted to seat upon and closely hug a part of the ball and 45 one side of the web of the rail.

12. A car-bumper section of plate formation provided upon one face with strengthening ribs, the section being adapted to seat upon and closely hug a part of the ball 50 and one side of the web of the rail and having an end wall arcuated to conform approximately to the curvature of a car-wheel.

13. A car-bumper section of plate formation provided upon one face with strengthening ribs and partly therearound with a marginal outwardly presented flange, the section being adapted to seat upon and closely hug a part of the ball and one side 55 of the web of the rail and an end wall of 60 the section being arcuated to conform approximately to the curvature of a car-wheel.

14. A car-bumper section of plate formation provided upon one face with strengthening ribs and partly therearound with a marginal outwardly presented flange, the section being adapted to seat upon and closely hug a part of the ball and one side 65 of the web of the rail and the end walls 70 of the section being arcuated to conform approximately to the curvature of a car-wheel.

In testimony whereof, we have signed our names to this specification.

HENRY E. BILLMAN.
FRANK A. KELL.
